Primary Examiner — Jasmine Mlinarcik(74) *Attorney, Agent, or Firm* — Dunlap Bennett & Ludwig, PLLC(57) **CLAIM**

The ornamental design for a head covering with aglets, as shown and described.

DESCRIPTION

FIG. 1 is a rear top right perspective view of the head covering with aglets, showing my new design;

FIG. 2 is a front elevation view thereof;

FIG. 3 is a rear elevation view thereof;

FIG. 4 is a left side elevation view thereof, with the right side elevation view being a mirror image thereof;

FIG. 5 is a top plan view thereof;

FIG. 6 is a bottom plan view thereof; and,

FIG. 7 is an enlarged detail rear elevation view thereof, indicated by line 7-7 of FIG. 3.

The broken lines shown in the drawings depict environment that forms no part of the claimed design.
